US0D1038793S

(12) **United States Design Patent** (10) Patent No.: **US D1,038,793 S**
(45) Date of Patent: ** Aug. 13, 2024

(54) **SENSOR ASSEMBLY**

(71) Applicant: **Waymo LLC**, Mountain View, CA (US)

(72) Inventors: **Jared Gross**, Belmont, CA (US); **Joshua Newby**, San Francisco, CA (US); **Albert Shane**, Berkeley, CA (US); **Alexandre Girard**, San Mateo, CA (US)

(73) Assignee: **Waymo LLC**, Mountain View, CA (US)

(**) Term: **15 Years**

(21) Appl. No.: **29/896,807**

(22) Filed: **Jul. 7, 2023**

Related U.S. Application Data

(63) Continuation of application No. 29/855,309, filed on Sep. 30, 2022, now Pat. No. Des. 996,996, which is a continuation of application No. 29/754,326, filed on Oct. 9, 2020, now Pat. No. Des. 968,981, which is a continuation of application No. 29/680,845, filed on Feb. 20, 2019, now Pat. No. Des. 902,756.

The ornamental design for a sensor assembly, as shown and described.

DESCRIPTION

FIG. 1 is a front side view of a sensor assembly according to a first embodiment of our design;

FIG. 2 is a rear side view thereof;

FIG. 3 is a front elevation view thereof;

FIG. 4 is a rear side elevation view thereof;

FIG. 5 is a left side elevation view thereof;

FIG. 6 is right side elevation view thereof;

FIG. 7 is a top plan view thereof;

FIG. 8 is a top perspective view thereof;

FIG. 9 is a front side view of a sensor assembly according to a second embodiment of our design;

FIG. 10 is a rear side view thereof;

FIG. 11 is a front elevation view thereof;

FIG. 12 is a rear side elevation view thereof;

FIG. 13 is a left side elevation view thereof;

FIG. 14 is right side elevation view thereof;

FIG. 15 is a top plan view thereof;

FIG. 16 is a top perspective view thereof;

FIG. 17 is a rear side view of a sensor assembly according to a third embodiment of our design;

FIG. 18 is a rear side elevation view thereof;

FIG. 19 is a perspective view of a sensor assembly according to a fourth embodiment of our design;
FIG. 20 is a front elevation view thereof;
FIG. 21 is a rear elevation view thereof;
FIG. 22 is a left side elevation view thereof;
FIG. 23 is a right side elevation view thereof;
FIG. 24 is a top plan view thereof;
FIG. 25 is a front side view of a sensor assembly according to a fifth embodiment of our design;
FIG. 26 is a rear side view thereof;
FIG. 27 is a front elevation view thereof;
FIG. 28 is a rear side elevation view thereof;
FIG. 29 is a left side elevation view thereof;
FIG. 30 is right side elevation view thereof;
FIG. 31 is a top plan view thereof;
FIG. 32 is a top perspective view thereof;
FIG. 33 is a front side view of a sensor assembly according to a sixth embodiment of our design;
FIG. 34 is a rear side view thereof;
FIG. 35 is a front elevation view thereof;
FIG. 36 is a rear side elevation view thereof;
FIG. 37 is a left side elevation view thereof;
FIG. 38 is right side elevation view thereof;
FIG. 39 is a top plan view thereof;
FIG. 40 is a top perspective view thereof;
FIG. 41 is a rear side view of a sensor assembly according to a seventh embodiment of our design;
FIG. 42 is a rear side elevation view thereof;
FIG. 43 is a perspective view of a sensor assembly according to an eighth embodiment of our design;

FIG. 44 is a front elevation view thereof;
FIG. 45 is a rear elevation view thereof;
FIG. 46 is a left side elevation view thereof;
FIG. 47 is a right side elevation view thereof;
FIG. 48 is a top plan view thereof;
FIG. 49 is a front side view of a sensor assembly according to a ninth embodiment of our design;
FIG. 50 is a rear side view thereof;
FIG. 51 is a front elevation view thereof;
FIG. 52 is a rear side elevation view thereof;
FIG. 53 is a left side elevation view thereof;
FIG. 54 is right side elevation view thereof;
FIG. 55 is a top plan view thereof;
FIG. 56 is a top perspective view thereof;
FIG. 57 is a front side view of a sensor assembly according to a tenth embodiment of our design;
FIG. 58 is a rear side view thereof;
FIG. 59 is a front elevation view thereof;
FIG. 60 is a rear side elevation view thereof;
FIG. 61 is a left side elevation view thereof;
FIG. 62 is right side elevation view thereof;
FIG. 63 is a top plan view thereof; and,
FIG. 64 is a top perspective view thereof.

The broken lines immediately adjacent to the shaded area define the bounds of the claimed design and form no part thereof. The broken lines illustrating the remainder of the sensor assembly form no part of the claimed design. The portions of the sensor assembly shown in a pattern or patterns of stipple illustrate areas of contrasting appearance.
